UNITED STATES PATENT OFFICE.

FREDERIC GEORGES BAUGATZ, OF PARIS, FRANCE.

ABDOMINAL BELT.

1,392,101.

Specification of Letters Patent. Patented Sept. 27, 1921.

Application filed May 20, 1918. Serial No. 235,563.

To all whom it may concern:

Be it known that I, FREDERIC GEORGES BAUGATZ, a citizen of the Republic of France, residing at 37 Boulevard des Capucines, 5 Paris, France, have invented certain new and useful Improvements in Abdominal Belts, of which the following is a specification.

The invention relates to abdominal belts 10 or similar articles, and particularly, to those intended to be worn by women during pregnancy.

It has for its object, principally, to provide an article which, while having sufficient elasticity to adapt itself to change of size of the abdomen, will serve, effectively, as a support for the lower part of the abdomen.

According to this invention the front part 20 of the band is of elastic fabric or of bands of elastic fabric arranged in such manner as to be extensible in the direction of the length of the band while the elasticity of the lower portion of the said front part is 25 reduced, by means, such as stitchings, bands or gores, extending at right angles or obliquely to the direction of elasticity, a lower non-elastic border being also provided, if desired.

30 Other features of the invention will be hereinafter more particularly described.

The invention will be understood from the following description and the accompanying drawings, which, however, are given 35 simply by way of example.

Figures 1 and 2 of the drawing show two explanatory views.

Fig. 3 shows, in front view, the front part of a band according to the invention.

40 Fig. 4 shows, in front view, the back part of the band.

Fig. 5 shows, in a side view, and on a similar scale, the band in place on the body of a woman.

45 Fig. 6 finally shows, in front view, the back part of a slightly modified band.

According to the invention, in making a band adapted to support the abdomen of a woman during pregnancy, that is to say a 50 band which, while holding the abdomen and supporting the lower part, allows it relatively considerable freedom particularly in the upper part, I may proceed as follows:

As shown in Figs. 1 and 2 a band of 55 elastic fabric α is taken, which is extensible in the direction of its length, that is to say

in the direction b b , and a certain number of suitable non-elastic elements are provided such, for example, as strips c of non-elastic material secured by stitching and extending 60 from the lower edge of the fabric at right angles or obliquely to the direction b b , up a certain distance from said edge, for instance one third of the height. These non-elastic elements are arranged at suitable intervals 65 whereby to effect a decided reduction of the elasticity of the part of the band to which they are applied, so that if the two ends of the fabric are stretched apart, equally over the whole width, the effect will be— 70 assuming that the part which does not include the stitchings or bands c is given a great extension—that the fabric will be drawn out in the shape of a fan, as shown in Fig. 2, the effect being considerably increased, if there is applied to the lower edge 75 d of the fabric a border of non-elastic fabric. Such a border may be formed, if desired, with interruptions.

To apply this arrangement to a band the 80 front part of it is formed of elastic material a (Fig. 3) arranged so that its elastic elements lie in the direction of the length of the band; and this material is cut to a suitable shape, for instance approximately to 85 the shape of a half-oval, the straight edge of which forms the upper edge of the band.

The lower part of the material is provided with a border of non-elastic material e , and, preferably, this border extends up to the 90 upper edge of the elastic material, so as to utilize the part e^1 of the side edges of the material a for connecting the front portion of the band to the back portion.

Non-elastic elements c are associated with 95 the fabric a , extending across the lower portion, that is from the lower edge toward the upper edge to an extent not exceeding one-half of the height of the fabric.

On the other hand, the back portion of the 100 band is suitably formed, either simply by an elastic band connected at its two ends to the edges e^1 of the front part by means of buttons or hooks, or by two elastic bands connected together at the middle of the back by 105 laces or other fastenings or, preferably, as shown in Fig. 4 by two sets of several elastic bands f^1 f^2 f^3 , arranged one above the other, and suitably connected as by stiffeners g , of whalebone, the two sets being connected 110 together either by buttons or, preferably, by lacing h , as in corsets.

In the latter case as the lacing at the back acts on strong whalebones or stiffeners, as shown in the drawings, the band provides a perfectly stiff back which supports the back 5 while supporting the front part in a suitable manner; that is to say conveniently supporting the lower part while allowing its normal development, owing to the lateral elastics and permitting the upper part of the abdomen 10 to develop more freely owing to the lateral elastics and to the elasticity of the upper front portion.

The stiff back part *h* of the band, may be in a single piece, or, preferably, in two parts 15 connected together, in any suitable manner, for example, by means of laces or straps, arranged so as to allow the two parts to be drawn together when the band is in position, this arrangement of the two parts allowing 20 the band to be undone from the back.

Preferably the back part is arranged relatively higher than the side part.

When the back *h* is made in two parts a third intermediate whalebone *h'* may be 25 added, as shown in Fig. 6, of variable dimensions thereby allowing the corset to be lengthened at the back, without letting out the lacing.

Preferably the edge *e* has several sets of 30 buttons or fastenings in order to allow, in a simple manner, the tightening of the band.

In this way a band is provided of which the front part while holding and supporting the abdomen from below, has sufficient elasticity, increasing from the base upward, to allow the abdomen the necessary freedom 35 during pregnancy.

Further in the case where the back part is formed in a rigid manner, the said back 40 part, owing to its rigidity acts as a solid support for the back and as a support for the lower portion of the front part.

This band allows pregnancy to develop normally, whereby the band can, without 45 any regulating be worn by a woman during the last four months of her pregnancy.

At the lower part, where the front part is 50 indeformable the lower side elastic bands *f*² can undergo a certain lengthening, this lengthening being such, for instance, as to 55 allow the band at the bottom to increase in circumference about 15 centimeters, which is enough to allow the necessary increase during pregnancy at the hips, while supporting the lower part of the abdomen; at the upper part, on the contrary, development 60 is not in any way interfered with, since, on the one hand, the side elastic bands *f*¹ can lengthen, for instance, 15 centimeters, while the upper portion of the front part can also extend, for instance from about 10 to 15 centimeters.

It will be understood that the band is formed so as to support chiefly the lower

part of the abdomen, without completely enveloping the infant, thus allowing the latter to develop freely above the band. Further, as shown in Fig. 5 the successive increase in size of the abdomen is represented by dotted lines, the arrow *i* indicating the principal direction of increase along which the band extends in supporting the infant, while the arrow *j* indicates the direction of support by the loins and by the lower inextensible part of the band. 75

Conveniently perineal straps may be arranged on the border *e*, being secured either directly or by buttons, thereby maintaining the band in position.

It will be understood that the invention is 80 not in any way limited to the arrangements more particularly indicated, but includes modified arrangements, particularly when in place of a single fabric *a*, several superposed elastic bands are employed. 85

What I claim is:—

1. A maternity band comprising a flat front part of elastic fabric expansible in the direction of the length of said band having the elasticity of the upper portion unimpeded throughout the length thereof, non-elastic elements arranged at intervals on the lower portion of said front part and secured to it so as to substantially reduce the elasticity of said lower portion, a non-elastic 90 border secured to said front part around its lower edge and a belt secured to said border and adapted to coöperate with the back of the wearer to support said front part in such a way that the supporting thrust is taken 100 solely by the portion of the reduced elasticity leaving the part of greatest elasticity freely expansible.

2. A maternity band comprising a flat front part of elastic fabric expansible in the direction of the length thereof, having the elasticity of the upper portion unimpeded throughout the length of the front part, non-elastic elements arranged at intervals on the lower portion of said front part and secured to it so as to substantially reduce the elasticity of said lower portion, a non-elastic border secured to said front part around its lower edge, said non-elastic elements being secured to said border and a belt secured to 110 said border and adapted to coöperate with the back of the wearer to support said front part in such a way that the supporting thrust is taken solely by the portion of reduced elasticity leaving the part of greatest 115 elasticity freely expansible.

In testimony whereof I have affixed signature in presence of two witnesses.

FREDERIC GEORGES BAUGAZ.
